ASSIGNORS TO WESTINGHOUSE ELECTRIC AND MANUFACTURING COMPANY, A
CORPORATION OF PENNSYLVANIA.

ACOUSTIC HORN.

Application filed February 4, 1924. Serial No. 690,405.

This invention relates to horns of the type used with sound-reproducing instruments such as phonographs, loud-speaking telephones and the like.

5 It is an object of this invention to improve the volume of tone and the quality of the sound, delivered through such horn, from a vibrating diaphragm.

The energy radiated from the horn in the 10 form of sound-waves is the quantity which determines how loud the sound seems to the listener. This depends not only upon the shape and size of the horn, the size of the diaphragm and the volume of the space 15 above the diaphragm, but also upon the velocity of the movement of the diaphragm. The relation between the energy radiated during a given short period and the average 20 velocity of the diaphragm during said period, may be expressed as a ratio, which is referred to herein as the intensification.

It is a further object of this invention to produce a horn which shall give an intensification that is substantially constant over a 25 great range of pitch.

In all instruments including a horn and a diaphragm, a function of the horn which has frequently been overlooked is to load the diaphragm by compelling it to do work 30 in moving the air within the horn and thus damping the motion of the diaphragm. It is a further object of this invention to so proportion this acoustic damping of the diaphragm to the other damping factors 35 that the sound distorting effect of the resonance of the diaphragm at its natural period shall be materially lessened. By making the acoustic damping large, we are enabled not only to diminish the radiated 40 power at diaphragm resonance, but to increase it at frequencies other than resonance. In this way, we produce a more uniform output throughout a range of frequencies without diminishing the average output.

45 It is a further object of this invention to provide acoustic damping to such degree as to prevent the diaphragm from vibrating beyond the amplitude within which the restoring forces are linear functions of the 50 displacement. If the diaphragm be permitted to vibrate more than this, the characteristic frequencies of the diaphragm itself begin to influence the output and dis-

tortion of the sound to be reproduced results. This object of the invention is, therefore, to 55 provide sufficient acoustic damping to prevent the amplitude of movement of the diaphragm from ever becoming great enough to introduce such distortions as can result from the characteristics which greater movements of the diaphragm possess.

It is a further object of this invention to so correlate the size of the opening at the large end of the horn to the length of the horn and the size of the small end that sufficient 60 radiation shall be obtained without requiring a horn of impractical length.

We have discovered, by mathematical analysis and confirmed by experiment, that the shape of the horn should be such that the 70 area of the cross-section is an exponential function of the distance from the small end of the horn.

The rate of increase of the cross-section of a horn having an exponential form plays 75 an important part, not heretofore understood, in determining a lower limit to the range of pitch over which the intensification will be uniform. Said rate also fixes the 80 length of the horn when the area of each end has been determined.

In the instruments heretofore used, the diameter of the opening at the small end of the horn has seldom been less than a fifth of the diameter of the diaphragm. We have 85 discovered that it is advantageous to make the opening at the small end of the horn very much smaller than this. The size of the throat of the horn must be correlated to the volume above the diaphragm. If the 90 opening be too small relative to this volume, the volume of air flowing through the throat will cease to be equal to the volume displaced by the movement of the diaphragm. When these two volumes begin to depart from 95 equality, further diminutions in the size of the throat does not result in a corresponding increase in acoustic damping. If the size of the throat relative to the volume above the diaphragm be too small, the velocity of air in the throat exceeds a certain critical value. Above this critical value, 100 turbulence occurs, with corresponding increase in friction losses. The lower limit of the size of the throat is fixed by consideration, both of the necessity of equality be-

tween the two volumes explained above and of the necessity for avoiding turbulence.

We have found that these considerations lead to very much smaller values, both of the cross-sectional area of the throat and of the volume of the chamber between the diaphragm and the throat, than have heretofore been usual.

In the sound-reproducing instruments of the prior art, it has been usual to have a cylindrical space between the diaphragm and the cover which opens into the horn. A cone contains only one-third the volume present in a cylinder of the same base and height and we reduce the volume of the space above the diaphragm still more by making it approximately conical. The height of the cone in the instrument we have devised is much less than the height of the space (of whatever shape) above the diaphragm in instruments used hitherto.

Other features of our invention and details of the construction will be readily understood from the following description and the accompanying drawing in which—

Fig. 1 is a view in side elevation of an instrument embodying this invention, and

Fig. 2 is a view on a larger scale partially in section and partially in elevation of the operating instrument and a portion of the horn.

A casing 1 contains mechanism for vibrating a diaphragm 2. This may be the electromagnetic mechanism of a loud speaker, a phonograph or any other means for actuating the diaphragm. A stem 3 is shown by way of example to indicate means by which the mechanism within the case 1 actuates the diaphragm 2.

The diaphragm is held in place by a cap 4 which is secured to the casing 1 in any desired manner. The edges of the diaphragm are clamped between the cap and the casing. The clamping action is cushioned by means of soft rubber washers 5 and 6. A recess is provided in the upper part of the cap in order to accommodate the upper washer. Preferably, the wall of this recess extends down over the inner surface of the washer, almost into engagement with the diaphragm.

From the lower edge of this wall, the inside of the cap slopes upwardly and inwardly, forming a cone 7. The drawing shows the height of this cone as small as can be illustrated with clearness. Actually, the height of the cone is relatively less. Preferably, it is only a few times the amplitude of the maximum movement of the diaphragm. Moreover, the movement of the diaphragm is much smaller in this instrument than in instruments having horns of the form used heretofore. Consequently, the width of the space 8 is very much smaller than in former instruments.

The opening 9 from the cap into the horn

is at the apex of the cone. This opening is much smaller than those in the horns used heretofore.

The horn 10 fits in the opening 8. The shape of this horn is given by the equation: 70

$$A = A_0 e^{Bx},$$

in which A is the area of the cross-section of the horn at the distance x from the small end, A_0 is the area of the opening at the small end, e is the Naperian base, and B is a constant which fixes the rate of increase of the cross-section.

The size of each end of the horn and its length, if definitely fixed, would determine 80 the constant B. Instead of thus determining it, we select a value for B which will prevent the length of the horn from being too inconvenient, when the areas of the ends are fixed, but this selection is based largely on considerations stated below. The selection must be a compromise between the range of pitch over which the horn will give uniform results and a convenient length.

We have found that for horns of exponential shape, B, the rate of increase of the cross-section, plays an important part in determining the lower limit of the range of pitch over which the intensification is sufficiently constant to prevent noticeable distortion. 95 This range is from very high pitches down to a pitch fixed by

$$\frac{\omega}{B} = 2.5 \times 10^4$$

100

where ω is 2π times the number of cycles per second for that pitch, and B is computed for a length measured in centimeters. The power radiated begins to diminish before this point is reached and falls off rapidly as 105 the pitch extends below this limit; but even so, the power radiated at low pitch is greater than for horns of other shapes. For example, it greatly exceeds that radiated by a conical horn, having the same length and 110 ends of the same respective areas at all low pitches except those very near the lower limit of audition.

The smaller the value of B, the lower the pitch at which effective radiation begins to 115 fall off; that is, the better the quality of the reproduction. On the other hand, a smaller value of B requires a longer horn for given sizes of the ends.

The size of the small end of the horn plays 120 an important part in determining the acoustic damping. Its area is given by the formula

$$A_0 = \frac{\rho a}{9} \sqrt{n-1} \quad \frac{A_d 2\omega_1}{\beta_0} \quad 125$$

in which ρ is the density of air, a the velocity of sound in air, n the permissible ratio of distortion, A_d the diameter of the diaphragm, ω_1 the period of the lowest frequency which 130

the horn is expected to radiate, and β_0 is the stiffness of the diaphragm. The stiffness of a diaphragm is the force tending to return it to normal position when it has been displaced.

The ideal instrument would radiate the same power at all pitches for the same force on the diaphragm. Such an instrument has not yet been discovered. With all known instruments there is more power radiated at certain frequencies than at others for the same force on the diaphragm. The ratio between the power radiated at the frequency where it is a maximum and at the frequency where it is a minimum, is what is termed in the preceding paragraph, the ratio of distortion n . It will be observed that in the above formula the area A_0 would be 0 if $n=1$. The several considerations pointed out above do not permit as small a value of n as unity. We have found that the distortion is not sufficient for the listener to notice it when n is not greater than ten.

$$V_0 = A_0 \frac{\omega_r^4 - \omega_1^2 \omega_2^2}{\frac{\rho a}{P_0} \omega_1 \omega_2 \left(-\frac{\omega_r^2}{\sqrt{n-1}} + \sqrt{\frac{n}{n-1} \omega_r^4 - \omega_1^2 \omega_2^2} \right)}$$

in which ω_r corresponds to the pitch at which the diaphragm is resonant, ω_2 corresponds to the highest note that is to be reproduced, P_0 is atmospheric pressure and the other symbols have the meaning already assigned to them.

When the frequencies are very high, the volume of the chamber above the diaphragm must theoretically be made smaller than the physical difficulties of manufacture permit. ω_2 may, however, be as large as 40,000 without the difficulties due to this circumstance appearing.

The area of the large end of the horn must be fixed by a compromise between the physical difficulties resulting from excessive length and the acoustic advantages which result from having this end very large. If the diameter of the final opening exceeds the wave length of the lowest pitch for which the horn is expected to correctly intensify, the reflections which take place at the large end will be negligible. It is found that this result is obtained when the radius of the

large end is $\frac{2}{B}$. This is the size which the large end of the horn has when its walls make an angle of 45 degrees with the axis. The lower limit of pitch for which the reflections are negligible is, with such a horn, the same as the pitch at which the intensification begins to fall off rapidly.

A horn of the dimensions stated above was used with a diaphragm having an area of 15.5 sq. cm. and a stiffness of 20×10^6 dynes per cm. over a range from somewhat

A practical horn which gives very good results has been constructed in which $B=0.07$ for c. m. units of length, which corresponds to approximately twenty per cent increase in area of cross-section per inch of length. This gave a falling-off point at $\omega=1250$, which corresponds to a pitch somewhat above middle c . The diameter of the small end is 0.508 cm. or 0.20 inches. The length is 132 cm. or about 4½ feet and the diameter at the large end 50.8 cm. or about 20 inches.

If this volume be too large in proportion to the area of the small end of the horn, the motion of the diaphragm, instead of being completely transformed into velocity of the air in the throat, may be partly expended in compressing the air within said volume. To obtain the desired uniformity of response over a desired range, the chamber volume must be not greater than that given by the formula

below middle c to 4-line c (c^{IV}). The conical chamber above the diaphragm had a height of .05 cm. With a constant current input, the greatest intensity throughout the pitch-range, was not more than ten times the smallest intensity. Such a horn, used with a loud-speaking telephone, gave a reproduction of music which was not only pleasing, but very close to the original. It gave a reproduction of voice which was not only intelligible, but natural.

When the diaphragm is actuated by a phonograph record, through a needle and lever system designed for use with an ordinary horn, greater power will be delivered from the record to the needle and greater volume of sound emitted by the horn. If desired, a different mechanical ratio may be employed in the needle-lever system, so that the displacement of the diaphragm is diminished. This would enable heavier members to be used in the lever system which tends to lessen the effect of resonance of those parts. The displacement of the whole system of needle, lever and diaphragm may thus be kept so small that tendency of this system to introduce resonance at certain pitches will be minimized. It is also possible to use, with the ordinary lever system, records prepared especially for use with such a horn. The undulations or sinuosities in such records would be of smaller amplitude than heretofore, which would be an advantage in the manufacture of such records. In all of these ways of applying the horn to a phonograph, the advantages obtained with

the greater acoustic damping causes greater freedom from tendency to radiate disproportionately large power at those pitches which correspond to the natural period of 5 free vibration of the moving parts.

Although we have described and illustrated but one particular embodiment of our invention, it is understood that changes within the spirit of the invention can be made 10 by those skilled in the art. We, therefore, do not purpose limiting the invention except as necessitated by the prior art or indicated in the claims.

We claim as our invention:

15 1. An acoustic horn, having an exponential variation of cross-section with the length and an internal diameter at the small end less than a third of an inch.

20 2. In combination, a diaphragm, a horn, an enclosure housing said diaphragm and opening into said horn, said opening being as small, relative to the volume of said enclosure, as may be without causing the volumetric flow of air into said opening to be 25 appreciably less than the volumetric rate of displacement of the diaphragm.

30 3. In combination, a diaphragm, means for vibrating said diaphragm, and acoustic means for so damping said vibration that the displacement of the diaphragm does not exceed an amount at which the restorative forces thereof cease to have a linear relation to said displacement.

35 4. In combination, a sound-reproducing device, a horn for acoustically damping the same, said horn having a cross section which is an exponential function of the distance from the small end and having a bell with walls making a maximum angle of forty-five degrees with the axis, and a throat, the minimum diameter of which is so small that the acoustic damping is greater than the sum of all other damping.

45 5. In combination, a diaphragm, a horn, a chamber closed at one side by said diaphragm and opening into the horn, and means for vibrating said diaphragm, said chamber closely conforming to one extreme position of said diaphragm and the area of 50 said opening being so small that the acoustic damping of the diaphragm prevents excursion thereof beyond the point of linear coefficient of stiffness.

55 6. In a sound-reproducing instrument, a horn, a diaphragm, an enclosure providing a chamber between said diaphragm and horn, said chamber opening into the throat of said horn, the area of said opening being large enough relative to the area of said diaphragm and volume of said chamber, to ensure the volumetric flow of air into the opening shall be equal to the volumetric rate of displacement of the diaphragm, and small enough to damp the motion of said dia-

phragm more than the sum of all other 65 damping.

7. An acoustic horn, having an exponential variation of cross-section with the length and an internal diameter at the small end less than two per cent of the internal 70 diameter at the large end.

8. An acoustic horn, the area of the cross-section of which is an exponential function of the distance from the small end, the diameter of the small end being less than one-half of one per cent of the length of the 75 horn.

9. An acoustic horn, having an exponential variation of cross-section with the length, the rate of increase of cross-section 80 per unit length being sufficiently small to bring the pitch limit of accurate reproduction within an octave of middle c.

10. An acoustic horn, the area of whose cross-section is an exponential function of 85 the distance from the small end, the rate of increase of the cross-section being less than twenty-five per cent per inch and the diameter of the opening at the small end being less than two per cent of the diameter of the 90 opening at the large end.

11. In a sound-reproducing instrument, a diaphragm, a conical housing covering said diaphragm, the altitude of the cone being less than one per cent of its base-diameter. 95

12. In a sound-reproducing instrument, a diaphragm, a horn, a conical housing covering said diaphragm and opening into said horn, the altitude of the cone being less than fifty times the maximum amplitude of the 100 motion of the diaphragm and the said opening being so small that the diaphragm does not move beyond the point at which the restorative forces thereof become a non-linear function of the displacement. 105

13. In a sound-reproducing instrument, a diaphragm, a conical housing covering said diaphragm and having an opening at its apex, the altitude of the cone being less than fifty times the maximum amplitude of the 110 motion of the diaphragm.

14. In a sound-reproducing instrument, a diaphragm, a horn, a housing over said diaphragm opening into said horn, the height of said housing being less than fifty times 115 the maximum amplitude of the motion of the diaphragm when loaded by said horn.

15. In a sound reproducing instrument, a chamber having an opening, and means co-operating with said chamber to produce an air movement in said opening corresponding to the sound to be reproduced, the area of said opening being such that the pressure within the chamber is maintained substantially constant. 120

16. In combination, a diaphragm, a horn, an enclosure housing said diaphragm and opening into said horn, said opening being 125

so proportioned, relative to the volume of said enclosure, that the volumetric flow of air through said opening will be substantially equal to the volumetric rate of displacement 5 of the diaphragm.

17. In combination, a diaphragm, a diaphragm chamber enclosing the same, a horn, the cross-sectional area of which increases by equal percentages for equal increases of 10 distance from the small end, the diaphragm chamber opening into the small end of the horn, the rate of increase of said cross-section, and the cross sectional area of the small end being such that the ratio of the damping 15 of the diaphragm by said horn to the mass of the diaphragm is greater than 10,000 e. g. s. units.

18. In an acoustic instrument, a diaphragm chamber, a diaphragm therein, a 20 horn, the cross section of which is an exponential function of the distance from the small end, the small end of said horn communicating with said diaphragm chamber, whereby the acoustic damping upon said dia- 25 phragm will be a function of the area of said small end of the horn, said area being so small that the acoustic damping per unit mass of the diaphragm is sufficient to prevent the ratio of sound energy radiated at 30 the natural resonance period of the dia- phragm to the sound energy radiated at the lowest frequency at which the horn can effectively radiate to be less than a normal ear can distinguish when listening to music.

35 19. In an acoustic instrument, a dia- phragm chamber, a diaphragm therein, a horn, the cross section of which is an exponential function of the distance from the small end, the small end of said horn com- 40 municating with said diaphragm chamber, whereby the acoustic damping upon said dia- phragm will be a function of the area of said small end of the horn, said area being so small that the acoustic damping is sufficient 45 to prevent perceptible distortion over the range of frequency for which the horn is in- tended.

20. In an acoustic instrument, a dia- phragm chamber, a diaphragm therein, a 50 horn, the cross section of which is an ex-

ponential function of the distance from the small end, the small end of said horn com- 55 municating with said diaphragm chamber, whereby the acoustic damping upon said dia- phragm will be a function of the area of said

small end of the horn, said area being so 60 small that the acoustic damping is sufficient to cause the radiated sound to be substan- tially independent of the frequency from the highest frequencies for which the instrument

is intended to the cut-off frequency deter- 65

21. In an acoustic instrument a dia- phragm chamber, a diaphragm therein, a horn, the cross section of which is an ex- 65 ponential function of the distance from the small end, the small end of said horn com- municating with said diaphragm chamber, whereby the acoustic damping upon said dia- phragm will be a function of the area of said 70 small end of the horn, said area being so small that the acoustic damping per unit mass is greater than $\frac{\omega_r^2}{3\omega_1}$ where ω_r is the nat- 75

ural resonance frequency of the diaphragm and ω_1 is the lowest frequency which the in- strument is expected to radiate.

22. In an acoustic instrument, a horn hav- 80 ing a cross section which is an exponential function of the distance from the small end, the rate of increase of said cross section being less than twenty-five percent per inch and the area of the large end being at least equal to that of a circle having $\frac{1}{B}$ for its 85 radius, where B is the constant in the ex- ponent determining said rate of increase.

23. In an acoustic instrument, a horn hav- 90 ing a cross section which is an exponential function of the distance from the small end, the area of the large end being greater than the area of a circle having a diameter equal to one-sixth of the wave length of sound at the frequency of the lowest natural resonance pitch of the horn. 95

In testimony whereof, we have hereunto subscribed our names this 30th day of January, 1924.

JOSEPH SLEPIAN.
CLINTON R. HANNA.
